UNITED STATES PATENT OFFICE.

ROSE FREED, OF PHILADELPHIA, PENNSYLVANIA.

CORSET.

1,413,578.

Specification of Letters Patent. Patented Apr. 25, 1922.

Application filed April 21, 1921. Serial No. 463,115.

To all whom it may concern:

Be it known that I, ROSE FREED, a citizen of the United States, residing at Philadelphia, in the county of Philadelphia and 5 State of Pennsylvania, have invented certain new and useful Improvements in Corsets, of which the following is a specification.

My present invention is designed to provide a corset or under garment, especially 10 for women's wear, which, in addition to performing its usual functions is adapted as an abdominal supporter. The invention consists essentially in a one-piece garment 15 that is to be stepped into when put on for personal wear, and is so constructed and fashioned as to be elastic to permit freedom of movement of the body, and at the same time insure a close body-fit for supporting 20 the organs of the wearer. The invention further consists in certain novel combinations and arrangements of parts whereby the garment is readily adaptable to the conformation or figure of the wearer, and involves 25 a detachable abdominal bandage which may be retained in position for effective use as a surgical appliance.

In the accompanying drawings I have 30 illustrated one complete example of the physical embodiment of my invention, involving two modes for its use, wherein the parts are combined and arranged according to the best manner I have thus far devised for the practical application of the principles 35 of my invention.

Figure 1 is a plan view of the corset in flat form, having a sanitary napkin attached thereto, and with its side openings at the top laced together. Figure 2 is a view 40 showing the garment in position for use, a portion only of the corset being shown in its detail of construction. Figure 3 is a view similar to Figure 1, but with the laces at the sides detached, and the top front flap of the 45 garment turned down to disclose the auxiliary or reinforcing elastic tapes, in this instance located at the inner sides of the upper edges of the corset. Figure 4 is a front view of the corset in use with the abdominal bandage in place. Figure 5 is a rear view. Figure 6 is a detail view of the detachable abdominal bandage.

As before stated the garment is in one piece, being knitted from silk, cotton, or 55 other desired thread, and in various sizes and colors, but of the general shape as shown

in the drawings to conform to the body of the wearer.

The body or trunk portion designated as 1 is of tubular formation, open at top and 60 bottom with flaring upper end 2 to conform to the outline of the bust and hips. A purling stitch is used in knitting the corset and vertically extending ribs 4 are thus provided forming an elastic garment that will 65 stretch laterally, but maintain its normal length or height. The difference between the contracted position and the extended position of the garment is readily seen in Figures 1 and 2, where the ribs lie in close proximity in the former figure, and in Figure 2 they are shown spaced apart with the garment adapted to the wearer's figure and the 70 position and extension of the ribs conforming to the figure.

At the upper flaring end of the garment are side openings 5, 5, along the borders or edges of which are stitched eyelets 6, and laces 7 are provided for the eyelets to draw 75 the edges together for securing the upper part of the garment in position.

Inside of the divided top edge of the garment I provide elastic tapes 8 and 9, that are stitched at regular intervals, as indicated at 10 in Figure 3, the stitches extending vertically, or in alignment with the ribs of the garment, in order that these tapes may be stretched longitudinally in conjunction with the lateral stretching of the garment body. These tapes, in addition to reinforcing the garment, also perform the function of rendering more rigid the upper part 85 of the garment in order that its shape may be maintained under all conditions, and of course the tapes extend around and conform 90 to the body of the wearer just below the bust.

Hose supporters 11 and 12 are arranged in pairs at the sides of the garment in such position that, when in use, they will extend 100 downwardly at the outer sides of the legs in convenient position and out of the way of the wearer, the usual attaching devices 13 being secured to the webs of the supporters for engagement with the hose or stockings. 105

The corset is also equipped with front and rear buttons 14 sewed thereto the proper distance above the lower edge of the corset, to which the sanitary napkin 15 may be buttoned. Adjacent the napkin, the garment, because of its elasticity, readily adapts itself without puckering, to the shape 110

of the legs and stomach, and in this manner comfort and convenience are insured to the wearer. When not required the napkin may be detached and dispensed with.

5 As before stated the garment is to be stepped into, and when removed, will be slipped over the feet, the elastic formation of the material readily lending itself to this performance, and, when the garment is in 10 use the elasticity insures a close body fit to the wearer.

It will be understood that the elastic reinforcing tapes 8 and 9 may be used both at the inner sides of the corset, as in Figures 15 1, 2, 3, and at the outer sides, as in Figure 4, or one tape may be stitched to the inner side and one at the outer side of the corset if desired. In any event the tapes will be effective in performing their required 20 functions of reinforcing the corset at the upper edges thereof.

In connection with the corset, I utilize an abdominal bandage, including a shield or pad 16 preferably made of elastic webbing, 25 or other elastic material may be used, and of a size and shape to comfortably and neatly fit over the abdomen, outside of the corset. Preferably the detachable pad is attached to the corset by means of the well 30 known type of glove fasteners or snap fasteners including snap buttons 17 secured near the top edge of the pad, and complementary eyes 18 at the front of the corset and near the top edge thereof.

35 Three retaining bands 19 are employed for retaining the pad in proper position, and also for reinforcing the action of the pad, and these bands are preferably of elastic webbing with their ends stitched at 20 40 for a permanent fastening to the pad. At the rear, the bands are held in proper spaced position by means of snap fasteners indicated by dotted lines at 21 in Figure 5, these fasteners being of the same type as those 45 for securing the pad to the corset at the front.

The pad and the bands, as seen in Figures 4 and 5 adapt themselves and conform

to the outline of the body of the wearer, and form a substantial support for the abdomen 50 and for the hips, at the same time providing, by their elasticity, for freedom of movement of the wearer without unnecessary restriction of the organs in the performance of their functions. 55

The pad and bands may be attached to the corset before the latter is stepped into, and because of the elasticity of all the parts, this may be accomplished with facility. When not required for use, the pad and 60 bandages may be quickly and conveniently detached by disengaging the fastening members 17—18 and 21, and removed, and the corset is used as illustrated in Figure 2.

Having thus fully described my invention, what I claim as new and desire to secure by Letters Patent is—

1. A tubular corset of elastic knitted fabric and formed with spaced vertically extending ribs, whereby the length of the 70 corset is normally retained but its width may be expanded, said corset having openings at the top on opposite sides and eyelets at the edges of said openings, laces in said eyelets, and elastic reinforcing members 75 for the top edges of the corset.

2. A tubular corset of elastic knitted material formed with spaced, vertically extending ribs, said corset being extensible circumferentially but comparatively rigid 80 along its vertical plane, openings at the top of the corset on opposite sides and eyelets in the edges of said openings, laces in said eyelets, and elastic webbing stitched at intervals along the upper edges of the corset 85 at the inner side between said openings.

3. A tubular corset of elastic material having top openings at opposite sides and laces therefor, combined with an elastic abdominal pad, encircling, elastic bands having their opposite ends permanently attached to the pad at the front, means for attaching said pad to the corset, and means at the rear for attaching said bands to the corset.

ROSE FREED.
